CLAIM

The ornamental design for a container for salad dressing or the like, shown and described.

DESCRIPTION

FIG. 1 is a front view of a container for salad dressing or the like showing our new design;

FIG. 2 is a side view thereof;

FIG. 3 is a top view thereof;

FIG. 4 is a rear view thereof; and,

FIG. 5 is a bottom view thereof.

The broken line showing in FIGS. 1 & 4 is for environmental purposes only and forms no part of the claimed design.
